UNITED STATES PATENT OFFICE.

JAMES H. STITES, OF DETROIT, MICHIGAN.

FIREPLACE.

1,400,329.

Specification of Letters Patent. Patented Dec. 13, 1921.

Application filed March 8, 1920. Serial No. 364,147.

To all whom it may concern:

Be it known that I, JAMES H. STITES, a citizen of the United States, residing at Detroit, in the county of Wayne and State of Michigan, have invented certain new and useful Improvements in Fireplaces, of which the following is a specification.

This invention relates to fire-places, and has for its object a prepared fire-place throat and smoke chamber lining which acts as a guide to a mason in building the fire-place. A great many masons are unskilled in properly building a fire-place so as to get the correct proportions, drafts, etc. This lining 15 acts as a pattern to build a fire-place along the lines of the best practice.

In the drawings,—

Figure 1 is a front elevation of a fire-place constructed in accordance with my invention.

Fig. 2 is a vertical section of the prepared lining on the line 2—2 of Fig. 3.

Fig. 3 is a vertical section of the lining taken from front to back.

Fig. 4 is a similar view showing the damper open.

Fig. 5 is a vertical section of the fire-place with my improved lining in place.

It is not broadly new to provide fire-place linings which in a measure form a guide for the mason in working in the fire-place, but so far as I am aware, the arrangement and construction of my prepared lining is new. In building a fire-place the fire brick *a* are usually pitched forwardly slightly at the back of the fire-place to form what is called the fire-back. It is set to incline forward for the purpose of causing the flames to turn forward and throw the heat out into the room. At the top of this fire-back the fire-place throat leading up into the chimney begins and ordinarily the damper is seated at this juncture. This fire-back top, which forms the smoke shelf, should always have a definite relation with respect to the top of the opening through the front of the fire-place. The smoke shelf should be somewhat removed above the front of the fire-place to give the best results and prevent the smoke getting out into the room. The smoke shelf serves to turn back any down draft in the chimney and prevents such down draft blowing the smoke of the fire back into the room. Furthermore, the damper should have a definite setting above the top of the opening through the front of the fire-place

as well as in relation to the smoke shelf. This is accomplished by my lining which comprises a four-sided inclosure preferably of sheet metal, rectangular in cross section, but of progressively smaller cross section from bottom to top to form the smoke chamber so as to give a suitable taper and concentration of the products of combustion between the large fire-place and the narrow flue up the chimney. This lining body designated *b* is adapted to seat on the top of the fire-back *a*, and is provided with turned-out flanges *w* which may be sealed into the rough brick work to form seats. In order to properly establish the relation of the top of the opening in the front of the fire-place with the smoke shelf, an apron *c* forms a continuation of the front wall of the lining body and depends from the lining body. This apron establishes the point at which the opening through the front of the fire-place should have its top. Where an arched opening is used, as shown in Fig. 1, the top of the arch does not go high enough to expose this apron.

At the top of the lining body the flue *d* of the chimney begins and can be provided with the usual flue tile *e*. Along the front of the lining body is an arched angular strip *f* which serves to seat the arch of the rough brick work *g* and act as a guide to the rough brick mason in laying in the arch. The finished brick *h* are put in later. The depending apron *c* tells the mason just where is to be located the fire-place opening. Of course, the rough brick mason is given the desired dimensions of the fire-place opening and he builds his fire-back and the throat of the fire-place leading up into the flue the proper height so that when the lining body is placed thereupon the bottom of the apron *c* will be just the required distance above the hearth *j* to give the proper depth to the fire-place opening, and the lining will seat upon the fire-back and establish the proper position of the smoke shelf with respect to the fire-place opening.

To the sides at the points *k* (Fig. 2) and to the front at the points *l*, is fastened the sheet metal strip *m* that forms the two ends in back of the damper casing. *n* represents the damper proper which is at *o* journaled in the ends of the damper casing. The angular arm *p* has its upper arm portion secured to the damper *n*. The lower arm portion is connected by a link *q* with the cam-follow-

ing arm *r* which straddles the damper stem *s*. This valve stem is rotatably mounted in the front wall of the lining body and in the back wall of the damper casing. The cam *t* is fastened to the valve-operating stem *s* with spacing sleeves *u* on either side of the cam. When the cam is turned, as shown in Fig. 3, the high part of the cam strikes the top of the cam-following arm *r* and closes the damper, as shown in this figure. When the damper-operating stem is turned through half a revolution the high part of the cam strikes the lower part of the cam-following arm and opens the valve, as shown in Fig. 4. This cam-following arm *r* is caused to pivot on the top and bottom edge of the end of the right hand sleeve *u* shown in Figs. 3 and 4. This forms an effective yet easily constructed and equipped valve casing and damper operating gear.

Some of the parts of the lining could be made in the form of castings, and hence I do not want to be limited to sheet metal except when so specified in the claims.

25. What I claim is:

1. A fire-place throat and smoke chamber lining comprising a main metal inclosure having dimensions at the bottom approximating the horizontal cross section of the

fire-place back of the opening and tapering 30 toward the top to approximate the dimensions of the flue opening, a subordinate inclosure secured in the main inclosure at the front and bottom to form the fire-place throat, the remainder of the main inclosure 35 thereby forming the smoke chamber, and a damper supported in the subordinate inclosure to regulate the opening through the said throat.

2. A fire-place throat and smoke chamber 40 lining comprising a main metal inclosure having dimensions at the bottom approximating the horizontal cross section of the fire-place back of the opening and tapering 45 toward the top to approximate the dimensions of the flue opening, a subordinate inclosure secured in the main inclosure at the front and bottom to form the fire-place throat, the remainder of the main inclosure thereby forming the smoke chamber, a 50 damper supported in the subordinate inclosure to regulate the opening through the said throat, and an apron extending down from the front of the main inclosure below the bottom thereof to define the top of the 55 fire-place opening.

In testimony whereof I affix my signature.
JAMES H. STITES.
